UNITED STATES PATENT OFFICE.

JOHN G. WHILLDIN, OF PHILADELPHIA, PENNSYLVANIA.

DESIGN FOR A FLOWER-POT.

SPECIFICATION forming part of Design No. 20,055, dated July 22, 1890.

Application filed June 28, 1890. Serial No. 357,154. Term of patent 7 years.

To all whom it may concern:

Be it known that I, JOHN G. WHILLDIN, a citizen of the United States, and a resident of Philadelphia, in the county of Philadelphia and State of Pennsylvania, have invented a certain new and useful Design for Flower-Pots; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a vertical central section. Fig. 2 is a bottom plan view.

This invention has relation to designs for flower-pots; and it consists in the novel form and configuration of parts, as hereinafter set forth.

In the accompanying drawings, the letter A designates the body portion of the pot, which is of the form of a frustum of a cone, surrounded by a re-enforced marginal portion

or offset B, of cylindrical or nearly cylindrical shape, and terminating below in the bottom C, which consists of the central plane portion d, having the semicircular marginal downward-projecting lugs e, separated at their ends by the concave notches f, and connected to said plane portion by the bevel faces g, as shown.

Having described this invention, what I claim, and desire to secure by Letters Patent, is—

The design for flower-pots, consisting of the conical body portion terminating below in the centrally-plane bottom portion having the semicircular lugs projecting downward, separated at their ends by the notches f, and connected to said plane portion by the bevel faces g, as shown.

In testimony whereof I affix my signature in presence of two witnesses.

JOHN G. WHILLDIN.
